(57) **CLAIM**

The ornamental design for a cap, as shown and described.

DESCRIPTION

FIG. 1 illustrates a perspective view of a cap;
FIG. 2 illustrates a front elevation view thereof;
FIG. 3 illustrates a back elevation view thereof;
FIG. 4 illustrates a side elevation view thereof;
FIG. 5 illustrates a side elevation view thereof;
FIG. 6 illustrates a top plan view thereof; and,
FIG. 7 illustrates a bottom plan view thereof.

The broken lines depict portions of the cap that form no part of the claimed design.
